FIG. 1 is a front perspective view of a lock showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines adjacent to the shade lines form a boundary of the design. Other broken lines illustrate the unclaimed portions of the design. None of the broken lines form no part of the claimed design.
